UNITED STATES PATENT OFFICE

2,098,800

CONNECTER

George B. Benander, Yalesville, Conn., assignor
to General Electric Company, a corporation of
New York

Application October 16, 1935, Serial No. 45,226

5 Claims. (Cl. 200—51)

My invention relates to connectors and more particularly to plugs adapted for use with a heating device.

An object of my invention is to provide an 5 improved connector of simple construction which may be readily assembled and is of low cost of manufacture.

What I consider to be novel and my invention will be better understood by reference to the following specification and appended claims when considered in connection with the accompanying drawing, in which Fig. 1 is a perspective view of my connector; Fig. 2 is a plan view of the connector with one of the body members removed; and Fig. 3 is a side view cut away to show the switch in the closed position; and Fig. 4 is a detail view of the switch mechanism.

Referring to the drawing, 10 indicates my improved connector with two complementary body members 11 and 12. Extending from one side of the connector 10 at an angle thereto is a strain relief spring 13 through which the cord connected to the connector is adapted to pass. 20 Since the strain relief 13 extends from the side of the connector 10, it is impossible for the plug to be removed merely by pulling on the cord. This method of removing the plug has been a source of many of the failures of plugs as the 25 cords frequently are broken at the point of passage into the connector as they are not able to withstand the repeated strain placed on the cord by the removal of the plug in this manner. By this arrangement, it is necessary to 30 grip the connector in order to remove it.

In order further to reduce the possibility of injury to the plug by its repeated removal to 35 open the circuit of the device to which the plug may be connected a switch 14 is provided. As 40 better indicated in Fig. 2, switch 14 is located at the top of the connector 10 and is mounted in the body member 11. Switch 14 is provided with a rocker operating handle 15 and is secured in position in body member 11 by means 45 of a screw 16 which is threaded into a metal insert 17 molded in the body member 11. In order to secure the operating mechanism of the switch 14 in position a plate 18 is provided with angularly extending legs 19 and 20 which seat in 50 slots provided in the complementary body members 11 and 12. A combined movable switch contact and operating member 21 is provided of U-shape with its free ends journaled in bearings 22 and 23 integral with plate 18. A 55 compression spring 24 is located between member

21 and operating handle 15. A stationary contact 25 is secured in member 11 by means of a screw 26 which may be threaded into a metal insert molded in the member 11. A binding screw 27 is threaded into contact 25 for connecting one of the conductors of the cord to the connector. A second stationary contact member 28 is provided and secured to a contact clip 29 by means of ears 30 turned down over side flanges of the contact clip 29. Contact 28 and contact 10 clip 29 are secured in member 11 by means of a screw 31. A second contact clip 32 is loosely located in position in member 11 and is provided with a binding screw 33 which is adapted to connect the other conductor of the cord to the 15 connector 10. In Fig. 2, the switch 14 is shown in the open position. To move the switch to the closed position, the projecting portion of rocker 15 is depressed to the position indicated in Fig. 3 where it is stopped by engagement 20 with one of the angular legs of plate 18. This movement of operating handle 15 compresses spring 24 and moves it over the center line of the switch moving the operating member 21 to the opposite position in engagement with the 25 stationary contacts 25 and 28. This completes the electrical connection from contact 25 through contact 28 to the contact clip 29.

In the assembly of the connector 10, the operating member is located in position with its 30 ends in the bearings 22 and 23 of plate 18. Plate 18 is then placed in position with its angularly extending arms 19 and 20 in the slots provided in member 11. Operating handle 15 is then secured in position by means of screw 16. Spring 35 24 is next placed in position between the operating handle 15 and operating member 21. The contact 28 and contact clip 29 after being connected together are secured in position in member 11 by means of screw 31. Contact 25 is 40 then secured in position by means of screw 26. Contact clip 32 and strain relief spring 13 are then located loosely in position in member 11. Member 12 is then placed over member 11 and secured to it by means of a bolt 34 and a 45 ring 35. Ring 35 fits over boss 36 formed on the side of members 11 and 12.

From the foregoing, it may be seen that an improved connector is provided consisting of a minimum number of parts which may be manufactured at a low cost and assembled with facility.

What I claim as new and desire to secure by Letters Patent of the United States is:

1. An electric connector comprising two com- 55

- plementary body members, a contact clip loosely mounted in said body members, a second contact clip and a stationary contact connected together and secured in one of said body members, a second stationary contact secured to one of said body members, a switch plate with angularly depending legs loosely mounted in said body members, a U-shaped switch contact journaled in depending bearings from said plate and adapted to bridge said stationary contacts, an operating handle secured at the top to one of said body members, and a spring interconnecting said operating handle and said switch contact.
15. 2. An electric connector comprising two complementary body members of insulating material, contact clips located in said body members, a stationary contact connected to one of said contact clips, a second stationary contact, a switch plate with angularly depending legs loosely mounted in said body members, a switch contact journaled in depending bearings of said plate and adapted to bridge said stationary contacts, a rocker secured and pivoted by a screw threaded in one of said body members, and a spring interconnecting said switch contact and said rocker.
30. 3. An electric connector comprising two complementary body members of insulating material, a contact clip loosely located in said body members, a second contact clip, a stationary contact connected to said last named contact clip, means to secure said stationary contact and said last named contact clip to one of said body members, a second stationary contact, means to secure said second stationary contact to one of said body members, a switch plate loosely mounted in said body members, a switch contact pivoted in bearings depending from said plate and adapted to 40 bridge said stationary contacts, a rocker handle

secured to one of said body members adjacent its top, a spring interconnecting said rocker and said switch contact, means to connect conductors to said first mentioned contact clip and said second stationary contact located at one side of said body member, an opening communicating with the side of said body members adjacent said last named means for the passage of conductors, and means to secure said body members together.

4. In an electric switch, spaced contacts, a supporting plate having an opening therein and angularly extending portions on each side of said opening, a handle having a part projecting through said opening, said handle being shaped to co-operate with said angularly extending portions to limit the movement thereof, spaced arms projecting from said plate on either side of the projecting portion of said handle, a switch blade journaled in said arms and arranged to co-operate with said contacts, and a spring connecting the switch blade and the projecting part of said handle for moving the blade with a snap action.

5. In an electric switch, a housing comprising complementary body members of insulating material, spaced contacts, a supporting plate having an opening therein and having angularly extending portions on either side of said opening, said angularly extending portions co-operating with said body member to loosely secure the plate therein, a handle projecting through said opening, said handle being shaped to co-operate with said angularly extending portions to limit the movement thereof, spaced arms projecting from said plate on either side of the projecting portion of the handle, a switch blade journaled in said arms, and a spring connected between the blade and the projecting portion of the handle for moving the blade with a snap action.

GEORGE B. BENANDER. 40
